8 Claims. (Cl. 211—122)

This invention relates to devices for storing and displaying rolls of merchandise in sheet-form as, for instance, floor coverings of various materials, which materials are rolled-up and stored in the form of a roll.

It is a general object of this invention to provide improved devices of the aforementioned description.

This invention refers more particularly to devices of the above description including a stand supporting four sprocket wheels arranged in spaced pairs in parallel vertical planes, each of said pairs supporting an endless revolving chain intended to support a horizontal rod at the axially outer ends thereof, which rod, in turn, is inserted into a roll of rolled-up merchandise and supports the latter.

Prior art storage and display devices of this type have a number of significant advantages, but also a number of significant drawbacks, or limitations.

It is, therefore, another object of this invention to provide storage and display devices of this type having all the significant advantages of the aforementioned prior art devices, but not being subject to any of the limitations of the prior art devices.

The most serious limitation of the aforementioned prior art devices is the difficulty involved in attaching rolls of merchandise to the revolving chains thereof and to remove rolls of merchandise from these chains.

It is, therefore, another object of this invention to provide storage and display devices for merchandise in the form of rolls suspended on a pair of revolving chains adapted to readily secure the rolls of merchandise to the chains and to readily remove the rolls of merchandise from the chains.

In prior art devices of the kind under consideration the roll-carrying chains are provided with pairs of hooks intended to engage the ends of a rod arranged inside of a roll of merchandise and projecting beyond the axially outer ends of such a roll. The roll of merchandise is placed on a carriage or cart supporting the roll exactly in the center region thereof, and when the carriage is raised and tilted in an appropriate fashion the aforementioned hooks on the revolving chains engage the axially outer ends of the aforementioned rod and lift the roll of merchandise from the carriage or cart.

Considering that rolls of floor covering have a diameter in the order of, say, 18 to 22 inches, a width of, say, 2-4 yards, and a weight of, say 4,000-8,000 lbs., it will be apparent that handling such a roll of merchandise in the aforementioned way amounts to an extremely difficult task. To lift the heavy rolls on the aforementioned carriage or cart, and to place them in the proper position on it, requires a great amount of physical strength and of dexterity.

Another way of securing the rolls of merchandise to the chains of the storing and displaying device is to perform this operation while the chains stand still rather than while the chains are revolving. This requires the cooperation of two persons of which one person lifts the projecting ends of the roll-supporting-rod arranged inside of the roll by means of a lever or bar, and the other person places the ends of the hooks which are sup-

2

ported by the chain under, and into engagement with, the raised ends of the roll-supporting-bar.

It is, therefore, another object of this invention to provide storing and displaying devices of the above description which are not subject to the aforementioned disadvantages, or drawbacks.

One might attempt to arrange the hooks on the revolving chains in such a fashion that they are automatically engaged by the projecting ends of the roll-supporting rod of a roll of merchandise properly placed between the revolving chains, such engagement taking place at a predetermined point of the trajectory of the hooks revolving jointly with the chains. This would mean that the outer surface of the roll of merchandise would be caused to frictionally engage the floor any time the particular roll of merchandise is lowered to the lowest position or level thereof, or lowered to the same position it had when automatically grabbed by the pair of hooks attached to the roll-carrying pair of chains. This is an intolerable condition. When frictionally engaging the floor the roll and the roll-supporting rod would have a tendency to rotate, and to thereby unwind a length of material from the roll. The tendency of joint rotation of the roll and of its supporting rod would exist to some extent in any position, or at any level, of these two parts.

It is, therefore, another object of this invention to provide storing and displaying devices of the aforementioned description having hooks adapted to automatically grab a roll of merchandise which is placed in the right position relative to the trajectory of the hooks, which devices are not subject to the aforementioned drawbacks and limitations, i.e. wherein the roll of merchandise is not caused to frictionally engage the floor when lowered to its lowest position, and wherein there is no tendency of unwinding of the merchandise at whatever level the roll of merchandise may be situated.

Other objects and advantages of the invention will, in part, be obvious and in part appear hereinafter.

For a fuller understanding of the nature and objects of the invention, reference should be had to the following detailed description and drawings in which:

FIG. 1 is a side elevation of a device embodying this invention;

FIG. 2 is a front elevation of the structure of FIG. 1;

FIG. 3 is a side elevation of details of the structure of FIGS. 1 and 2 showing these details in a first position and on a larger scale than FIGS. 1 and 2;

FIG. 4 is a front elevation of the details shown in FIG. 3;

FIG. 5 is a side elevation of the details shown in FIG. 3 on the same scale as FIG. 3 showing these details in a second position, or other position than in FIG. 3;

FIG. 6 is a front elevation of the details shown in FIG. 5; and

FIG. 7 is a longitudinal section of two plate chain links forming part of the chain of the structure of FIGS. 1 and 2.

Referring now to the drawings, numeral 1 has been applied to indicate a pair of spaced uprights or columns. Columns 1 are joined by a pair of prismatic horizontal beams 2. Beams 2 are rectangular in cross-section and form jointly with uprights 1 a stand which is dimensionally very stable. Each upright 1 supports a bearing 1^a adjacent its upper end. Bearings 1^a support a shaft 3 which, in turn, supports a pair of sprocket wheels 4. Sprocket wheels 4 are arranged adjacent the axially outer ends of shaft 3 immediately adjacent to uprights 1 and bearings 1^a. Each upright 1 further supports a bearing 1^b arranged at a substantially lower level than bearing 1^a. Each bearing 1^b supports a pivot pin 5 which, in turn, supports a sprocket wheel 4. Each of the sprocket wheels 4 positioned at a higher level is arranged in registry with

one of the sprocket wheels positioned at the lower level. The bearings 1^b are provided with means (not shown) for changing their level within predetermined limits. The left pair of sprocket wheels 4 (FIG. 2) supports a chain 6 made up of plate links, and the right pair of sprocket wheels 4 supports a chain 6 identical to the first-mentioned chain. Reference numeral 4^a has been applied to indicate the spaces between contiguous sprockets of sprocket wheels 4. These spaces are substantially semi-circular in cross-section, and their diameter conforms to that of hollow pins 6^a used for joining contiguous plate links to form a link chain 6. FIG. 7 clearly shows the fashion in which links of chain 6 in the form of spaced pairs of plates are joined together by hollow pins 6^a, i.e. pins having a central bore or passageway 6^b. The constituent links of the chain 6 are spaced by tubular spacers 6^c. It will be apparent from the foregoing that the chains 6 mounted on and supported by wheels 4 are chains of the kind known as plate link chain, or Galle's chain.

Shaft 3 is provided with an appropriate drive (not shown). This may either be a motor drive or a manual drive, as desired.

Reference letter W has been applied to indicate a roll of material in sheet-form which may have a considerable weight. Roll W defines on the inside thereof a tubular space enclosing a hollow core of cardboard. Preparatory to supporting roll W on the stand or frame structure 1, 2, a hollow supporting rod 7 is inserted into the hollow cardboard core of roll W. Hollow rod 7 supports on the axially outer ends thereof a pair of tubular extensions 7^a defining passages 7^b. Extensions 7^a engage the radially inner surface of hollow supporting rod 7, and are arranged eccentrically inside of rod 7. Both extensions 7^a are arranged in registry, i.e. along the same generatrix of cylindrical supporting rod 7. Supporting rod 7 and roll W may be attached to the two chains 6 supported by wheels 4 by means of pins 8, 8^a inserted into the cylindrical passageways 6^b of hollow chain pins 6^a. Pins 8, 8^a include a head 8 and a shank 8^a which projects into one of the passageways 7^b defined by extensions 7^a of hollow rod 7. Reference numeral 8^b has been applied to indicate pin members in the nature of cotter pins projecting transversely through extensions 7^a and shanks 8^a for precluding relative movements of these parts in a direction longitudinally thereof.

The structure embodying this invention further comprises a mechanism for conveniently securing rolls W of merchandise to the revolving chains 6 on wheels 4. This mechanism includes a pair of plates 9 having an integral pin 9^a, 9^b arranged at right angles to the plane defined by plate 9 and inserted into the passageway 6^b formed by one of the pins 6^a by which the plate links of the two chains 6 are joined together. Reference character 9^a has been applied to indicate the side of pin 9^a, 9^b projecting into one of the passageways 6^b defined by one of the hollow pins 6^a and reference character 9^b has been applied to indicate the side of pin 9^a, 9^b projecting from the opposite side of plate 9. Each of the pair of plates 9 is provided with a second pin 9^c which is integral with it and arranged parallel, and in spaced relation, to pin 9^a, 9^b. Reference numeral 9^d has been applied to indicate a pair of rods each having a transverse aperture 9^d at the upper end thereof engaged by the pins 9^c integral with plates 9. Each rod 9^d forms on the lower end thereof a hook 9^e. Hooks 9^e are intended to engage the axial extensions 7^a of rod 7 while the chains 6 on wheels 4 are revolving, and thus to lift roll or rolls W from the floor. FIGS. 3 and 4 show how hooks 9^e engage extensions 7^a in the process of lifting a roll W of merchandise from the floor upon which it had been resting.

Assuming that a roll W of merchandise had been lifted in the above described manner to a level of about 1 yard above ground or floor level, in this position of roll W the

latter cannot yet be pinned by means of pins 8, 8^a to the two revolving chains 6 because the passageways 6^b of pins 6^a are not yet in registry with the passageways 7^b of the axial extensions 7^a of hollow rod 7. Reference character x has been applied to indicate the spacing between extensions 7^a and the passageways 6^b defined by contiguous pins 6^a of chain 6. In order to be able to pin extensions 7^a to the two revolving chains 6 on wheels 4, the distance x must be reduced to zero. To be more specific, pins 8, 8^a can be inserted at any time into passageways 6^b of pins 6^a, but in order to be able to push pins 8^a in a direction longitudinally thereof into extensions 7^a of hollow rod 7, the passageways 6^b and 7^b must be aligned, or arranged in coaxial relation. This can readily be achieved by operating bell-crank-shaped handle levers 9^g of which one is arranged immediately adjacent to each upright 1. Each lever 9^g is provided with two holes 9^h, 9ⁱ for receiving the ends 9^b of pins 9^a, 9^b and for receiving pins 9^c. The ends 9^b of pins 9^a, 9^b and pins 9^c enter into holes 9^h, 9ⁱ whenever handle levers 9^g are arranged in their operating position along chains 6. Handle levers 9^g are a means for pivoting plates 9 about their pins 9^a, 9^b from the position shown in FIGS. 3 and 4 to the position shown in FIGS. 5 and 6. Pins 9^c when pivoted jointly with plates 9 move the upper ends of hook-shaped rods 9^e along circular trajectories resulting in gradual lifting of extensions 7^a until the difference x between the level of extensions 7^a and that of the closest pair of hollow pins 6^a becomes zero, and passageways 6^b, 7^b are in coaxial positions. This then makes it possible to insert pins 8, 8^a all the way into passageways 6^b, i.e. to such an extent that shanks 8^a of pins 8, 8^a enter into passageways 7^b of extensions 7^a. When this is achieved, roll W of merchandise is supported by pins 8, and 8^a on the revolving chain drive. This makes it possible to remove levers 9^g, rods 9^e and plates 9 from the chain drive, to be kept in preparedness for the next operation of the same kind, i.e. for the next operation of aligning axial extensions 7^a on a hollow roll-supporting rod 7 with a pair of hollow chain pins 6^a.

When the hollow roll-supporting rods 7 are in a position in which they are solely supported by pins 8, 8^a rather than by the hook-shaped ends 9^f of rods 9^e, the lowest level assumed by roll W during its travel is so high as to preclude roll W from ever touching the floor on which uprights 1 are standing and from which roll W had been lifted. This is apparent from a consideration of FIGS. 1 and 2 showing that the spacing of extensions 7^a from the floor is approximately equal to the radius of roll W as long as the roll W rests on the floor or on the ground, including the instant extensions 7^a are being grabbed by the hook-shaped ends 9^f of rods 9^e. At any time after the suspension of roll W has been transferred from the hook-shaped rods 9^e to pins 8, 8^a the spacing of extensions 7^a from the ground or floor exceeds the radius of roll W and, therefore, roll W will not slide on the ground after its suspension has been transferred from hook-shaped rods 9^e to pins 8, 8^a.

In the preferred embodiment of the invention the stand 1, 2 is adapted to receive rolls W of merchandise of different width. This calls for a change of the distance between the two uprights 1. As shown in FIG. 2 beams 2 include a telescoping portion 2', shaft 3 includes a telescoping portion 3' and hollow rod 7 includes a telescoping portion 7'. These telescoping portions 2', 3' and 7' make it possible to vary at will the distance between the two uprights 1. Parts 2, 3 and 7 are provided with transverse holes intended to receive cotter pins to maintain the length of parts 2, 3 and 7 once it has been selected.

As shown in FIG. 2 the upper beam 2 supports a bracket 2^b for a bearing 2^a supporting shaft 3.

Shaft 3 may be operated by an electric motor by the intermediary of a self-locking worm gear drive (not shown) adapted to move the chains 6 on wheels 4 selec-

tively in either of two directions. If it is preferred to operate the device manually rather than by an electric motor, shaft 3 is preferably arranged in such a way that it supports the two lower sprocket wheels 4 rather than the upper sprocket wheels 4 and one of the lower sprocket wheels 4 is associated with an appropriate manually operable crank mechanism.

If desired uprights 1 may be provided with casters (not shown) to make it possible to readily change the location of the device.

It appears from the foregoing that extensions 7^a are not arranged in coaxial relation to roll W of merchandise. As a result, roll W has no tendency to roll about extensions 7^a and thus to unroll, or unwind, unintentionally some of the merchandise. When merchandise is unrolled from roll W a certain resistance against unwinding must be overcome, and it is quite easy to overcome that resistance.

It will be understood that a plurality of rolls W of merchandise may be mounted on the chains 6 on stand 20 1, 2 in the same fashion as has been explained above in connection with one single roll W.

The structure or toggle mechanism 9^b, 9^c 9 for lifting a roll W of merchandise may also be used for lowering the level of a roll W of merchandise. Assuming that it is intended for one reason or another to remove a roll W of merchandise from the stand of FIGS. 1 and 2; this can be achieved by arranging the structure 9^b, 9^c 9 on the system of chains 6 in the position shown in FIGS. 5 and 6, thereupon removing pins 8, 8^a supporting hollow rod 7 30 on its extensions 7^a, and thereafter lowering levers 9^c as a result of which the constituent parts of the device are moved from their positions shown in FIGS. 5 and 6 to their positions shown in FIGS. 3 and 4. It will thus be apparent that the process of removing a roll W of merchandise from the revolving chain drive is the reverse of the process of securing a roll W of merchandise to that drive.

While, in accordance with the patent statutes, I have disclosed the details of a preferred embodiment of my invention, it is to be understood that many of these details are merely illustrative and variations in their precise form will be possible, or necessary, depending on the particular nature of application.

I desire, therefore, that my invention be limited only to the extent set forth in the appended claims, and by 45 the prior art.

I claim as my invention:

1. A device for storing and displaying rolls of rolled-up merchandise in sheet-form, such as floor coverings of various materials, comprising in combination: 50

- (a) a pair of uprights;
- (b) substantially horizontal beams joining said pair of uprights to form a stand jointly with said pair of uprights;
- (c) a first pair of sprocket wheels arranged at a relatively low level each adjacent one of said first pair of uprights and supported by said stand;
- (d) a second pair of sprocket wheels arranged at a relatively high level each adjacent one of said pair of uprights and supported by said stand; 60
- (e) a pair of endless plate link chains each supported by one of said first pair of sprocket wheels and one of said second pair of sprocket wheels, said pair of chains including hollow link-connecting pins;
- (f) a pair of hooks each pivotally supported on one end thereof by one of said pair of chains; 65
- (g) manually operable means for varying the spacing between the points of pivotal support of said pair of hooks and said link-connecting pins of the pair of chain links of said pair of chains immediately adjacent said points of pivotal support; and
- (h) pin means for supporting rolls of merchandise, said pin means being inserted into a pair of hollow link-connecting pins and projecting at right angles axially 70

inward from the pair of planes generally defined by said pair of chains.

2. A device for storing and displaying rolls of rolled-up merchandise in sheet-form, such as floor coverings of various materials, comprising in combination:

- (a) a pair of uprights;
- (b) substantially horizontal beams joining said pair of uprights to form a stand jointly with said pair of uprights;
- (c) a first pair of sprocket wheels arranged at a relatively low level each adjacent one of said pair of uprights and supported by said stand;
- (d) a second pair of sprocket wheels arranged at a relatively high level each adjacent one of said pair of uprights and supported by said stand;
- (e) a pair of endless plate link chains each supported by one of said first pair of sprocket wheels and one of said second pair of sprocket wheels, said pair of chains including hollow link-connecting pins;
- (f) a pair of toggle mechanisms supported by pin means inserted into a first pair of said hollow link-connecting pins, each of said pair of toggle mechanisms including a hook forming a fulcrum at one point thereof, and each of said pair of toggle mechanisms further including a manually operable lever for varying the spacing between said first pair of hollow link-connecting pins and said fulcrum of said hook; and
- (g) pin means for supporting rolls of merchandise, said pin means being inserted into a second pair of said hollow link-connecting pins and projecting at right angles axially inward from the pair of planes generally defined by said pair of chains.

3. A device for storing and displaying rolls of rolled-up merchandise in sheet-form, such as floor coverings of various materials, comprising in combination:

- (a) a pair of uprights;
- (b) substantially horizontal beams joining said pair of uprights to form a stand jointly with said pair of uprights;
- (c) a first pair of sprocket wheels arranged at a relatively low level each adjacent one of said pair of uprights and supported by said stand;
- (d) a second pair of sprocket wheels arranged at a relatively high level each adjacent one of said pair of uprights and supported by said stand;
- (e) a pair of endless plate link chains each supported by one of said first pair of sprocket wheels and one of said second pair of sprocket wheels, said pair of chains including hollow link-connecting pins;
- (f) a pair of first pin means inserted into a first pair of hollow link-connecting pins;
- (g) a pair of plates pivotally supported by said first pair of pin means, each of said pair of plates being provided with a pin spaced from, and extending parallel to, said first pin means;
- (h) a pair of members each having a hook-shaped end and each having an aperture at one end thereof remote from said hook-shaped end engaged by said pin on one of said pair of plates;
- (i) a pair of bell-crank-shaped operating levers, each of said pair of operating levers having a pair of parallel bores, one of said pair of bores being engaged by said first pin means, and the other of said pair of bores being engaged by said pin on one of said pair of plates; and
- (j) pin means for supporting rolls of merchandise, said pin means being inserted into a second pair of said hollow link-connecting pins and projecting at right angles axially inward from the pair of planes generally defined by said pair of chains.

4. A device for storing and displaying rolls of rolled-up merchandise in sheet-form, such as floor coverings of various materials, comprising in combination:

- (a) a pair of uprights;
  - (b) substantially horizontal beams joining said pair of uprights to form a stand jointly with said pair of uprights;
  - (c) a first pair of sprocket wheels arranged at a relatively low level each adjacent one of said pair of uprights and supported by said stand;
  - (d) a second pair of sprocket wheels arranged at a relatively high level each adjacent one of said pair of uprights and supported by said stand;
  - (e) a pair of endless plate link chains each supported by one of said first pair of sprocket wheels and one of said second pair of sprocket wheels, said pair of chains including hollow link-connecting pins;
  - (f) a supporting bar for rolls of merchandise having tubular extensions projecting axially outwardly from the ends thereof and being arranged in registry parallel to the longitudinal axis of said supporting bar and in spaced relation from said axis;
  - (g) a pair of hook-members each pivotally supported on one end thereof by one of said pair of chains and each forming a hook on the other end thereof for engaging one of said extensions of said supporting bar;
  - (h) manually operable means for varying the spacing between said one end of each of said pair of hook members and said link-connecting pins of said pair of chains immediately adjacent to said one end of each of said pair of hook members; and
  - (i) a pair of pin means inserted into a pair of said hollow link-connecting pins and projecting into said tubular extensions of said supporting bar.
5. A device for storing and displaying rolled-up merchandise in sheet-form, such as floor coverings of various materials, comprising in combination:
- (a) a pair of uprights;
  - (b) substantially horizontal beams joining said pair of uprights to form a stand jointly with said pair of uprights;
  - (c) a first pair of sprocket wheels arranged at a relatively low level each adjacent one of said pair of uprights and supported by said stand;
  - (d) a second pair of sprocket wheels arranged at a relatively high level each adjacent one of said pair of uprights and supported by said stand;
  - (e) a pair of endless plate link chains each supported by one of said first pair of sprocket wheels and one of said second pair of sprocket wheels, said pair of chains including hollow link-connecting pins;
  - (f) a cylindrical hollow supporting bar for rolls of merchandise having tubular extensions integral with said bar, inserted into the ends of said bar and projecting axially outwardly from the ends of said bar, said extensions being arranged along the same generatrix of said bar and in spaced relation from the longitudinal axis of said bar;
  - (g) a pair of toggle mechanisms supported by pin means inserted into a first pair of said hollow link-connecting pins, each of said pair of toggle mechanisms including a hook forming a fulcrum on one end thereof and being shaped on the other end thereof for engagement of one of said tubular extensions of said supporting bar, each of said pair of toggle mechanisms further including a manually operable lever for varying the spacing between one of said first pair of hollow link-connecting pins and said fulcrum of said hook of one of said pair of toggle mechanisms; and
  - (h) a pair of pin means inserted into a second pair of said hollow link-connecting pins each projecting into one of said tubular extensions of said supporting bar.
6. A device for storing and displaying rolls of rolled-up merchandise in sheet-form, such as floor coverings of various materials, comprising in combination:
- (a) a pair of uprights;

- (b) substantially horizontal beams joining said pair of uprights to form a stand jointly with said pair of uprights;
  - (c) a first pair of sprocket wheels arranged at a relatively low level each adjacent one of said pair of uprights and supported by said stand;
  - (d) a second pair of sprocket wheels arranged at a relatively high level each adjacent one of said pair of uprights and supported by said stand;
  - (e) a pair of endless plate link chains each supported by one of said first pair of sprocket wheels and one of said second pair of sprocket wheels, said pair of chains including hollow link-connecting pins;
  - (f) a cylindrical hollow supporting bar for rolls of merchandise having tubular extensions integral with said bar, inserted into the ends of said bar and projecting axially outwardly from the ends of said bar, said extensions being arranged along the same generatrix of said bar and in spaced relation from the longitudinal axis of said bar;
  - (g) a pair of plates each having one of first pair of pin means engaging one of first pair of said hollow link-connecting pins, each of said pair of plates being provided with a pin spaced from, and extending parallel to, one of said first pair of pin means;
  - (h) a pair of members each having a hook-shaped end and each having an aperture at one end thereof remote from said hook-shaped end engaged by said pin on one of said pair of plates;
  - (i) a pair of bell-crank-shaped operating levers, each of said pair of operating levers having a pair of parallel bores, one of said pair of bores being engaged by one of said first pair of pin means, and the other of said pair of bores being engaged by said pin on one of said pair of plates; and
  - (j) a pair of pin means inserted into a second pair of said hollow link-connecting pins each projecting into one of said tubular extensions of said supporting bar.
7. A device for storing and displaying rolls of rolled-up merchandise in sheet-form, such as floor coverings of various materials, comprising in combination:
- (a) a pair of spaced uprights;
  - (b) substantially horizontal beams joining said pair of uprights to form a stand jointly with said pair of uprights, said horizontal beams comprising telescoping portions to vary the spacing between said pair of uprights;
  - (c) a pair of horizontal bearings each supported by one of said pair of uprights;
  - (d) a horizontal shaft supported by said pair of bearings at the ends thereof, said shaft comprising telescoping portions to vary the length thereof;
  - (e) a first pair of sprocket wheels supported by said shaft and adjacent one of the ends thereof;
  - (f) a second pair sprocket wheels supported by said stand each arranged in a plane defined by one of said first pair of sprocket wheels;
  - (g) a pair of endless plate link chains each supported by one of said first pair of sprocket wheels and one of said second pair of sprocket wheels, said pair of chains including hollow link-connecting pins;
  - (h) a pair of hooks each pivotally supported on one end thereof by one of said pair of chains;
  - (i) manually operable means for varying the spacing between the points of pivotal support of said pair of hooks and said link-connecting pins of said pair of chains immediately adjacent said points of pivotal support; and
  - (j) pin means for supporting rolls of merchandise, said pin means being inserted into a pair of hollow link-connecting pins and projecting at right angles axially inward from the pair of planes generally defined by said pair of chains.

8. A device for storing and displaying rolls of rolled-up merchandise in sheet-form, such as floor coverings of various materials, comprising in combination:
- (a) a pair of spaced uprights;
  - (b) substantially horizontal beams joining said pair of uprights to form a stand jointly with said pair of uprights, said horizontal beams comprising telescoping portions to vary the spacing between said pair of uprights;
  - (c) a pair of horizontal bearings each supported by one of said pair of uprights;
  - (d) a horizontal shaft supported by said pair of bearings at the ends thereof, said shaft comprising telescoping portions to vary the length thereof;
  - (e) a first pair of sprocket wheels supported by said shaft and adjacent one of the ends thereof;
  - (f) a second pair of sprocket wheels supported by said stand each arranged in a plane defined by one of said first pair of sprocket wheels;
  - (g) a pair of endless plate link chains each supported by one of said first pair of sprocket wheels and one of said second pair of sprocket wheels, said pair of chains including hollow link-connecting pins;
  - (h) a cylindrical hollow supporting bar for rolls of merchandise having tubular extensions integral with said bar, inserted into the ends of said bar and projecting axially outwardly from the ends of said bar, said extensions being arranged along the same generatrix of said bar and in spaced relation from the longitudinal axis of said bar, said bar comprising telescoping portions to vary the length thereof;

- (i) a pair of plates each having one of a first pair of pin means engaging one of a first pair of said hollow link-connecting pins, each of said pair of plates being provided with a pin spaced from, and extending parallel to, one of said first pair of pin means;
- (j) a pair of members each having a hook-shaped end and each having an aperture at one end thereof remote from said hook-shaped end engaged by said pin on one of said pair of plates;
- (k) a pair of bell-crank-shaped operating levers, each of said pair of operating levers having a pair of parallel bores, one of said pair of bores being engaged by one of said first pair of pin means, and the other of said pair of bores being engaged by said pin on one of said pair of plates; and
- (l) a pair of pin means inserted into a second pair of said hollow link-connecting pins each projecting into one of said tubular extensions of said supporting bar.
